SHAVING IMPLEMENT

Nicholas Testi, Boston, Mass., assignor to Gillette
Safety Razor Company, Boston, Mass., a cor-
poration of Delaware

Application May 12, 1936, Serial No. 79,295

5 Claims. (Cl. 30—43)

This invention relates to shaving implements of the type employing co-operating shearing members for the cutting operation.

In one aspect the invention comprises the combination of a rotary shearing element with a blade having a longitudinal cutting edge maintained in contact with the surface of the rotary element and suitable guard members for determining the angle of presentation of the implement to the face of the user. As herein shown, the rotary element may take the form of a helix mounted to revolve about its longitudinal axis and the blade may be flexible transversely so that its edge may be brought accurately into cutting relation with the helix. This construction is advantageous in that it permits accurate adjustment of the shearing elements and because it is effective yieldingly to maintain the proper pressure of engagement and adjustment. As herein shown, the edge-bearing portions of the blade may be arranged resiliently to engage the surface of the helix, or the edge-bearing portions of the blade may be rigidly supported and the helix mounted for yielding bodily movement.

An important feature of the invention consists in the combination of a rotary cutting helix with a blade having a serrated edge co-operating therewith. Under some circumstances, and particularly in the case of a cutting helix having an obtuse cutting angle, there is an objectionable tendency to displace sideways the hairs which are acted upon by the cutting edge, so that the hairs are either not cut or not closely cut. These difficulties are avoided in accordance with the present invention by serrating the edge of the cutting blade forming in effect pockets which receive the hairs and prevent their displacement, acting instead to hold the hairs stationary during the shearing operation which is effected by the movement of the helix.

In another aspect my invention comprises broadly a duplex shaving implement employing oppositely rotating cutting elements having the capacity of operating with equal efficiency when moved transversely in either directions over the face of the user. In this connection another feature of the invention consists in the combination with a pair of spaced cutting helices of a double-edged blade so mounted that the two edge-bearing portions thereof may be adjustably positioned in proper shaving relation with the two helices respectively.

In the implement of my invention the blade is replaceably mounted so that it may be readily removed for purposes of cleaning or replacement.

The blade, moreover, is a relatively inexpensive element and may be replaced at little expense by the user when it becomes worn in the operation of the implement.

These and other features of the invention will be best understood and appreciated from the following description of certain preferred embodiments thereof, selected for purposes of illustration and shown in the accompanying drawing, in which:—

Fig. 1 is a view of the implement in end elevation, partly in section and on an enlarged scale;

Fig. 2 is a fragmentary sectional view on a still further enlarged scale;

Fig. 3 is a plan view in actual size of the blade of the implement;

Fig. 4 is a fragmentary view of the blade on a greatly enlarged scale;

Figs. 5, 6 and 7 are fragmentary views of three different forms of blade, each being shown with an associated cutting helix;

Figs. 8, 9 and 10 are fragmentary views in elevation illustrating three different forms of cutting helices;

Fig. 11 is a view in end elevation of a modified form of implement;

Fig. 12 is a view in longitudinal section of the head of the implement shown in Fig. 11; and

Fig. 13 is a fragmentary view in cross-section and on an enlarged scale of another modified form.

The implement shown in Fig. 1 has a tubular handle 10 to which is secured a horizontally disposed cylindrical casing 12 substantially equal in length to a commercial safety razor blade. In the cylindrical casing is mounted a small rotary motor which is supplied with energy through the wires 11 encased in the handle 10. The field poles 13 of the motor, with the field windings, are secured to the inner walls of the casing 12 and the armature 14, mounted on a shaft 15, is journaled in the end walls of the casing. A driving gear 16 is secured to one end of the shaft 15 and this in turn is gear-connected to a pair of spaced parallel cutting helices mounted to rotate at opposite sides of the implement. The left-hand helix 20 is driven in a clockwise direction by the gear 16 through an idle pinion 17 and a driving pinion 18 which is fast to the end of the helix shaft 19. The right-hand helix 20 is driven in a counterclockwise direction through the medium of two idle pinions not herein shown. The idle pinions and the helix shaft 19 are journaled in plates 28, one secured to each end of the casing 12 by suitable screws.

Each helix is partially encased in a curved trough formed by a guard flange 21 which extends upwardly as an integral part of the casing and is curved about the outer side of the helix. 5 The upper edge of the guide flange is slotted to form guard teeth 23 and these have the function of protecting the face of the user from the uncontrolled action of the helix and also to direct the hairs to the helix and to straighten those 10 which may happen to be bent over. The action of the guard teeth 23 is best suggested in Fig. 2 of the drawing. The helix 20 comprises a pair of spiral portions sharpened longitudinally to a cutting edge and being fluted circumferentially to 15 afford liberal clearance.

Arranged to co-operate with the two cutting helices is a normally flat, thin, double-edged blade 26 which is arranged to be supported upon a shouldered platform formed as an integral part 20 of the casing 12. The blade is flexed transversely over the shoulders 22 as fulcrums by a curved cap member 24 having a downwardly disposed concave blade-engaging face of greater width than the spacing of the shoulders 22. The 25 cap member 24 is adjustably clamped in place by means of a thumb screw 25 and it will be understood that by turning the thumb screw 25 in or out the position of the two cutting edges may be adjusted to a nicety with respect to the helices. 30 The cap may be provided, if desired, with a pair of spaced blade-locating studs 29 which are arranged to pass through the blade-locating slot of the blade 26 into sockets provided for that purpose in the platform or blade-supporting face 35 of the casing 12.

As shown in Figs. 3 and 4 both longitudinal bevelled edges of the blade 26 are notched to 40 form the serrated edges 27. The serrations extend inwardly for about one-third of the distance of the bevel so that the thickness of the blade at the inner end of the slots is approximately .002". Consequently, the length of the stubble need not exceed the thickness of the blade at this point. Figs. 8, 9 and 10 illustrate 45 different forms of cutting helices. The helix 20 includes a pair of cutting portions arranged with a relatively long pitch. The helix 32 of Fig. 9 is characterized by a single spiral cutting portion of much shorter pitch and the helix 33 has even 50 a shorter pitch and a correspondingly more obtuse cutting angle as indicated in Fig. 7. Any one of the three helices shown may be employed with satisfactory results in the illustrated implement and other forms of cutting helices would be within the scope of the invention. The purpose of serrating the cutting edges of the blade 55 is primarily to provide a series of projections which tend to hold the hairs in place against the tendency of the spiral edge of the helix to displace it. This tendency is more pronounced in the case of such a helix as that of Fig. 10, where the cutting angle is obtuse, than in the case of such a helix as that of Fig. 8, where the cutting angle is more acute. As already pointed out the 60 depth of the serrations determines the line of cut and the thickness of the blade interposed between the surface of the helix and the face of the user.

The blade 26 is maintained in position in the 70 implement by the vertical clamping screw 25 and may be quickly released for purposes of replacement or cleaning merely by unscrewing the clamping screw 25. The degree of transverse curvature of the blade may be also adjusted by 75 manipulation of the screw 25 and the edges of

the blade may thus be adjusted correctly to a position of cutting contact with the surface of the respective helices. In this position the edge-bearing portions of the blade occupy a substantially tangential relation to the helices. 5

It will be understood, of course, that in operation the helices are rotated continuously at a high rate of speed and in opposite directions, that is to say, at their upper sides both helices move inwardly toward the blade 26. The guard 10 teeth 23 and the longitudinal edges of the cap member 24 constitute guard means for determining the angle of presentation of the implement to the face of the user and also to prevent the skin from bulging inside the cutting line where 15 it would be damaged by the rotation of the helix. The implement as a whole is moved transversely across the face of the user in either direction and in this movement the hairs which are directed to the helix in the advancing side of the 20 implement are sheared by the co-operative action of the rotary helix and the serrated blade edges which they encounter.

In Figs. 11 and 12 is illustrated a somewhat different mechanical organization embodying my 25 invention. This implement is operated by a vertical motor disposed within a cylindrical casing 40 and supplied with energy by wires 41 which enter its lower end. A part of the armature 42 is shown in Fig. 12. The armature shaft 30 43 is journaled in the upper end of the casing and provided with a worm 44. A frame 45 is secured to the upper end of the casing 40 and to the ends of this are secured a pair of vertically movable end plates 46. The end plates are secured to the frame by pin and slot connections and are normally urged upwardly by curved leaf springs 39 which are secured upon opposite sides to the hub of the frame 45 and engaged beneath the lower edges of the plates. Journaled in the 40 end plate 46 is a pair of spaced transverse shafts 38, each of which is provided with a centrally disposed worm gear, not shown, by which the two shafts are driven from the worm 44 on the motor shaft. Each shaft 38 is provided at one 45 end with a drive pinion 49 and the latter meshes with a driven pinion 50 fast upon the end of a shaft carrying rotary cutter 51 which may correspond to the cutting helices shown in Figs. 8, 9 or 10. It will be noted that this worm gear drive 50 is such as to impart rotation to the two cutting helices in opposite directions and, accordingly, the direction of rotation of the motor is made such as to rotate both helices inwardly at their upper sides. 55

The frame 45 constitutes a blade support having parallel fulcrum shoulders over which a thin double-edged blade 52 may be flexed transversely by a concave cap member 47, the latter is adjustably maintained in position upon the frame 60 by a vertical thumb screw 48. The portion of the implement illustrated in Figs. 11 and 12 is similar to that already described except that the end plates assembled with the spaced helices journaled therein are urged upwardly at all 65 times so that yielding contact is maintained between the helices and the opposite edges of the blade 52. The position and curvature of the blade may be regulated by turning the thumb screw 48 in or out, although the blade may be rigidly clamped in position and the resiliency of contact derived wholly from the yielding mounting of the helices. If desired, the edge-bearing portions of the blade may be brought 75

into substantial tangential relation with the helices.

Still another form of implement embodying the invention is partially illustrated in Fig. 13. 5 In this instance, a pair of cutting helices 61, one only being shown, is journaled in end plates yieldingly mounted upon the frame 60 and these helices are arranged to co-operate with a substantial rigid concave cutting member 62 which 10 is provided with oppositely disposed cutting edges and is clamped in position upon the frame 60 by a thumb screw 63. The cutting member 62 is in this instance clamped rigidly in shaving position while the helices are maintained yieldingly in operative relation thereto by being mounted in movable end plates as that already 15 explained in connection with the implement of Figs. 11 and 12.

Having thus described my invention what I 20 claim as new and desire to secure by Letters Patent of the United States is:—

1. A dry shaving implement having, in combination, a cylindrical motor casing having a blade support thereon and spaced parallel troughs 25 therein, a flexible blade located upon the support and overhanging both of said troughs, a rotary cutter in each trough, and a motor in said casing having connections for driving the cutters in opposite directions while yieldingly engaged by 30 opposite edges of the blade.

2. A dry shaving implement having, in combination, a blade with oppositely disposed cutting edges, a co-operating cutting helix mounted for

rotation under each edge of the blade and resiliently supported in contact therewith, and means for driving the helices in opposite directions.

3. A shaving implement having, in combination, spaced rotary cutting helices, a power-driven shaft, separate gear trains between said shaft and the respective helices for driving the helices in opposite directions, a double-edged blade maintained with its edges substantially in contact with the respective helices, and guard members associated therewith. 5 10

4. A shaving implement having, in combination, a pair of rotary cutting helices arranged in spaced parallel relation, a power operated element, separate gear trains for connecting said element and the respective helices for driving the helices at substantially the same speed, a blade support located above said helices, and means for transversely flexing a double-edged blade on said support to bring its edges into 20 cutting relation with the respective helices. 15

5. A shaving implement having, in combination, a pair of rotary cutting helices arranged in spaced parallel relation, a blade supported between said helices, a power-driven shaft, separate 25 gear trains located between said shaft and one end of the respective helices for rotating them at substantially the same rate of speed, and means for adjustably flexing the blade to position its opposite edges in cutting relation with the re- 30 spective helices.

NICHOLAS TESTI.
